(57) **ABSTRACT**

Disclosed are a low power driving system and timing controller for a display device. The low power driving system for a display device may include a timing controller configured to transmit a packet to which one of first option information corresponding to a static pattern or second option information corresponding to a dynamic pattern is applied, and a source driver configured to receive the packet and to perform a low power mode corresponding to the static pattern based on the first option information or adaptive charge sharing corresponding to the dynamic pattern based on the second option information.

LOW POWER DRIVING SYSTEM AND TIMING CONTROLLER FOR DISPLAY DEVICE

BACKGROUND

1. Technical Field

The present disclosure relates to a low power driving technology, and more particularly, to a low power driving system and timing controller for a display device.

2. Related Art

A display device includes a timing controller, a source driver, and a display panel.

The timing controller may be designed to provide the source driver with display data for display, control data, and a clock in a packet form. The source driver receives the display data, and provides the display panel with a source signal corresponding to the display data. The display panel displays a screen corresponding to the source signal.

The display device is required to adopt a technology for reducing power consumption in various elements. To this end, the adoption of a technology for reducing power consumption of the timing controller and the source driver is actively examined.

Furthermore, the source driver of the display device may have a structure for a unique charge sharing connection or an all-charge sharing connection for the output of a source signal.

Accordingly, the display device needs to be designed to provide the source driver with an option for reducing power consumption according to various packet types or a charge sharing structure, such as all-charge sharing.

SUMMARY

Various embodiments are directed to providing a low power driving system and timing controller for a display device, which can support a source driver that uses a charge sharing method including an all-charge sharing connection.

Furthermore, various embodiments are directed to providing a low power driving system and a timing controller, which can freely provide an option for reducing power consumption with respect to a polarity and perform a power consumption operation according to the option.

Various embodiments are directed to providing a low power driving system and method and timing controller for a display device, which can reduce consumption power of a source driver by recognizing, by a timing controller, a display pattern and transmitting, to the source driver, option information corresponding to the recognized display pattern.

Furthermore, various embodiments are directed to providing a low power driving system for a display device, which can reduce consumption power by providing a packet including option information capable of reducing power consumption in accordance with a display pattern and performing charge sharing control over an output based on the option information or performing current control over at least one of an output buffer, a gamma buffer, and an intermediate driving voltage (HVDD) buffer.

In an embodiment, a low power driving system for a display device may include a timing controller configured to receive packet data for correcting a polarity of line data, correct polarities of previous line data and current line data based on the packet data, divide a display pattern into a static

pattern and a dynamic pattern based on a difference between the previous line data and the current line data, and transmit a packet to which one of first option information corresponding to the static pattern and second option information corresponding to the dynamic pattern is applied, and a source driver configured to receive the packet and perform a low power mode corresponding to the static pattern based on the first option information or adaptive charge sharing corresponding to the dynamic pattern based on the second option information.

In an embodiment, a timing controller for a display device may include a pixel value storage configured to store previous line data and current line data and provide the previous line data and the current line data for mapping, a packet receiver configured to receive packet data for correcting a polarity of line data based on the packet data, a packet mapper configured to map information on the polarity of the line data based on the packet data, a pixel value correction unit configured to correct information on polarities of the previous line data and the current line data based on the information on the polarity, an operation unit configured to receive the previous line data and the current line data from the pixel value correction unit and to calculate a power gain quantity and power loss quantity attributable to charge sharing for the current line data based on a result of a comparison between the previous line data and the current line data or calculate a first maximum change in an output of the source driver in which charge sharing is applied to the current line data and a second maximum change in the output of the source driver in which charge sharing is not applied to the current line data, and an option information providing unit configured to provide second option information on whether to apply the charge sharing to the current line data based on a result of a comparison between the power gain quantity and the power loss quantity, if a display pattern is a dynamic pattern and to provide, as first option information, one change selected from the first maximum change and the second maximum change depending on whether to apply the charge sharing to the previous line data, if the display pattern is a static pattern.

BRIEF DESCRIPTION OF THE DRAWINGS

FIG. 1 is a block diagram illustrating a low power driving system for a display device according to an embodiment of the present disclosure.

FIG. 2 is a flowchart illustrating a lower power driving method according to the embodiment of FIG. 1.

FIG. 3 is a block diagram of a timing controller illustrated in FIG. 1.

FIG. 4 is a flowchart illustrating an operation of a packet mapper illustrated in FIG. 3.

FIG. 5 is a flowchart illustrating an adaptive charge sharing control operation.

FIGS. 6 and 7 are exemplary diagrams of a panel structure.

FIG. 8 is a block diagram for describing an all-charge sharing connection applied to an embodiment of the present disclosure.

FIG. 9 is a flowchart illustrating an operation of controlling a low power mode.

FIG. 10 is a waveform diagram for describing an operation of controlling a low power mode according to an output level of a source driver.

FIG. 11 is a graph illustrating an output change slope of the source driver according to time corresponding to option information.

DETAILED DESCRIPTION

Exemplary embodiments will be described below in more detail with reference to the accompanying drawings. The disclosure may, however, be embodied in different forms and should not be construed as limited to the embodiments set forth herein. Rather, these embodiments are provided so that this disclosure will be thorough and complete, and will fully convey the scope of the disclosure to those skilled in the art. Throughout the disclosure, like reference numerals refer to like parts throughout the various figures and embodiments of the disclosure.

A low power driving system for a display device according to an embodiment of the present disclosure may be illustrated as in FIG. 1.

Referring to FIG. 1, a timing controller 10, a source driver 20, a display panel 30, and a memory 40 are illustrated.

The timing controller 10 receives display data, a packet type and packet data, wherein the display data is received from the outside. The packet type may be received along with the display data. The timing controller 10 may receive packet data, corresponding to a packet type, from a lookup table stored in the memory 40.

In this case, the memory 40 may be configured to store and provide the packet data using an EEPROM, for example. The packet data includes information on a polarity of line data.

The timing controller 10 is configured to configure externally received display data in the form of a packet PKT and provide the packet PKT to the source driver 20.

In this case, the timing controller 10 may configure the packet PKT including display data and control data. The control data may include various types of option information for distinguishing between power control modes.

The timing controller 10 may correct the polarity of a pixel value of line data using packet data, and may generate the option information based on a result of a comparison between previous line data and current line data whose polarities have been corrected.

The power control modes may be classified into a low power mode control operation and an adaptive charge sharing control operation. The option information may represent low power mode control or adaptive charge sharing control, may have a value according to a predetermined protocol, and may be applied to the packet PKT by being included in the control data.

The source driver 20 receives a packet PKT from the timing controller 10 and outputs, to the display panel 30, a source signal (Sout) corresponding to display data. In this case, the source driver 20 may be configured to perform a power control mode corresponding to option information of control data in a process of converting the display data into the source signal (Sout) and a process of outputting the source signal (Sout).

The source driver 20 may include a latch, a shift register, a digital-to-analog converter, and an output buffer for the conversion of the display data. Furthermore, the source driver 20 may include a gamma buffer for providing a gamma voltage to the digital-to-analog converter and an intermediate driving voltage (HVDD) buffer for providing a driving voltage to the output buffer.

Since the latch, the shift register, the digital-to-analog converter, the output buffer, the gamma buffer, and the

intermediate driving voltage buffer are components commonly used in the source driver 20, detailed illustrations and descriptions thereof are omitted.

The display panel 30 may be configured as a flat display panel. Illustratively, a display panel including pixels using an organic light-emitting diode (OLED), a light-emitting diode (LED) or a liquid crystal display (LCD) may be used as the display panel 30.

In the configuration of FIG. 1, the low power driving system for a display device according to an embodiment of the present disclosure are configured to include the timing controller 10 and the source driver 20.

An operation of the low power driving system for a display device is described with reference to FIG. 2.

First, the timing controller 10 is configured to divide a display pattern into a static pattern and a dynamic pattern based on a difference between previous line data and current line data and to transmit a packet PKT to which one of first option information corresponding to the static pattern and second option information corresponding to the dynamic pattern is applied.

The timing controller 10 performs a control process. The control process may include step S10 of recognizing a pattern and providing a packet PKT, including control data having the first option information or the second option information, based on the recognized pattern.

The source driver 20 may receive a packet PKT, and may recognize a power control mode based on the first option information or the second option information. More specifically, the source driver 20 is configured to perform a low power mode control operation, corresponding to a static pattern, based on the first option information or an adaptive charge sharing control operation, corresponding to a dynamic pattern, based on the second option information.

That is, the source driver 20 performs a driving process based on the recognized power control mode. The driving process includes step S20 of recognizing the power control mode based on a display pattern, step S22 of performing the low power mode if the display pattern is a static pattern, and step S23 of performing adaptive charge sharing if the display pattern is a dynamic pattern.

The display pattern may be determined as one of the static pattern and the dynamic pattern by comparing previous line data and current line data.

Furthermore, a determination criterion for distinguishing between the static pattern and the dynamic pattern may be set as a data change between the previous line data and the current line data. A criterion for the data change for distinguishing between the static pattern and the dynamic pattern may be variously set depending on a manufacturer's intention.

Among the static pattern and the dynamic pattern, the static pattern may be defined as a case where source signals (Sout), that is, the output of the source driver 20, are constantly maintained because a data change between previous line data and current line data is small.

Furthermore, the dynamic pattern may be defined as a case where source signals (Sout), that is, the output of the source driver 20, swing because a data change between previous line data and current line data is great.

In an embodiment of the present disclosure, if a display pattern is a static pattern, the timing controller 10 is configured to provide the first option information for determining a power control mode as the low power mode control operation. The source driver 20 is configured to perform the low power mode for reducing consumption power by reduc-

ing the amount of current that maintains an output for current line data based on the first option information.

Furthermore, in an embodiment of the present disclosure, if a display pattern is a dynamic pattern, the timing controller **10** is configured to provide the second option information for determining a power control mode as the adaptive charge sharing control operation. The source driver **20** is configured to perform the adaptive charge sharing for reducing consumption power in a way to provide a current, discharged from a load capacitor of the display panel, to the place that needs to be charged, by performing charge sharing on the output of current line data based on the second option information.

The timing controller **10** provides a packet **PKT**, including the first option information or the second option information in control data, in order to reduce consumption power of the source driver **20**. To this end, the timing controller **10** may be configured as in FIG. 3.

The second option information may be determined and provided by an adaptive charge sharing control operation of FIGS. 4 and 5. The first option information may be determined and provided by a low power mode control operation of FIGS. 4 and 9. The adaptive charge sharing control operation and the low power mode control operation may be understood to be included in step S10 of FIG. 2 of recognizing a pattern and providing a packet **PKT**, including control data having the first option information or the second option information, based on the recognized pattern.

First, referring to FIG. 3, the timing controller **10** includes a data receiver **11**, a packet configuration unit **12**, a packet output unit **13**, and an option information configuration unit **15**.

The data receiver **11** transmits externally received display data to the packet configuration unit **12**. The packet configuration unit **12** provides the packet output unit **13** with the display data, control data, and a clock for configuring a packet **PKT** as parallel data. The packet output unit **13** converts the parallel data into serial data according to a predetermined protocol, and transmits the serial data to the source driver **20** as the packet **PKT**.

In the above configuration, the packet configuration unit **12** receives the first option information or the second option information provided by the option information configuration unit **15**, and operates so that the first option information or the second option information is included in the control data.

The option information configuration unit **15** is configured to correct the polarity of line data based on packet data and to provide the first option information or the second option information based on a result of a comparison between previous line data and current line data. To this end, the option information configuration unit **15** includes a packet receiver **2**, a packet mapper **4**, a pixel value storage **5**, a pixel value correction unit **6**, an operation unit **7**, and an option information providing unit **9**.

The packet receiver **2** receives packet data for correcting the polarity of line data based on the packet data.

The packet type may be received along with display data or may be previously set in an internal memory (not illustrated).

The packet receiver **2** may receive the packet data, corresponding to the packet type, from the lookup table stored in the memory **40**.

The packet mapper **4** maps information on a polarity of the line data based on the packet type and the packet data. That is, the packet data may be determined based on the packet type. The information on a polarity of line data for

each channel is mapped based on the packet data. Accordingly, the packet data may be understood as data for mapping the information on the polarity for each line.

The pixel value storage **5** may be configured as a memory for storing display data, transmitted from the data receiver **11** to the packet configuration unit **12**, in a line unit. The pixel value storage **5** is configured to have a capacity capable of storing at least previous line data and current line data and providing the previous line data and the current line data for mapping. Furthermore, the pixel value storage **5** may be configured to store display data in a line unit and provide previous line data and current line data, stored therein, for mapping, in synchronization with control and an operation of the option information providing unit **9**.

The pixel value correction unit **6** corrects information on polarities of previous line data and current line data based on information on a polarity of line data for each channel, provided by the packet mapper **4**, and provides the operation unit **7** with the previous line data and the current line data having the corrected polarities.

The operation unit **7** receives the previous line data and current line data from the pixel value correction unit **6**. The operation unit **7** may perform an operation of computing a data change by mapping the previous line data and the current line data, an operation of determining a display pattern in response to the data change, an operation of calculating a power gain quantity (Ps) and a power loss quantity (Pw) attributable to charge sharing for the current line data, an operation of comparing the power gain quantity (Ps) and the power loss quantity (Pw), and an operation of detecting maximum changes (Lpeak_{cs} and Lpeak_{ncs}) in the output of the source driver, if the charge sharing is applied to the current line data and if the charge sharing is not applied to the current line data, respectively. The operation unit **7** may perform some operations, selected from the operations, based on a display pattern, and provides the results of the operations to the option information providing unit **9**.

The operation unit **7** may receive, from the packet mapper **4**, information on a polarity of line data for each channel, for the operations, and may perform the operations based on a positive polarity and a negative polarity.

The option information providing unit **9** may control the operation unit **7** to select an operation to be performed in accordance with a display pattern, receives the results of the operation, determines option information corresponding to the display pattern, and provides the determined option information to the packet configuration unit **12**.

That is, the option information configuration unit **15** may determine the second option information obtained by performing the adaptive charge sharing control operation of FIGS. 4 and 5 or the first option information obtained by performing the low power mode control operation of FIGS. 4 and 9, and may provide the determined first option information or second option information to the packet configuration unit **12**.

The low power mode control operation of FIG. 4 is performed by the packet mapper **4** of FIG. 3. FIG. 4 illustrates that information on a polarity of line data for each channel is mapped based on packet data determined based on a packet type (S11) and polarity mapping for each channel based on the packet data is performed (S12) after the mapping based on the packet type (S11) is performed.

The operation of the packet mapper **4** in FIG. 4 is incorporated into a line data correction step S34 based on the polarity of a channel in the adaptive charge sharing control operation of FIG. 5 and a line data correction step S73, based

on the polarity of a channel in the low power mode control operation of FIG. 9, and steps S34 and S73 will be described later.

The adaptive charge sharing control operation of FIG. 5 is performed if a display pattern is a dynamic pattern.

The adaptive charge sharing control operation is described in brief. The adaptive charge sharing control operation includes correcting previous line data and current line data to each have a polarity mapped for each channel based on packet data, calculating a power gain quantity (Ps) and power loss quantity (Pw) attributable to charge sharing for the current line data by mapping and comparing the previous line data and the current line data, and determining whether to apply the charge sharing to the current line data by comparing the power gain quantity (Ps) and the power loss quantity (Pw).

That is, the second option information according to the adaptive charge sharing control process may be understood as information indicating whether to apply charge sharing to a source signal corresponding to the current line data.

Furthermore, the low power mode control operation of FIG. 9 is performed if a display pattern is a static pattern.

The low power mode control operation is described in brief. The low power mode control operation includes correcting previous line data and current line data to each have a polarity mapped for each channel based on packet data, mapping and comparing the previous line data and the current line data, detecting a first maximum change in the output of the source driver 20 in which charge sharing is applied to the current line data, and selecting the first maximum change as a first option level. Furthermore, the low power mode control operation includes mapping and comparing the previous line data and the current line data, detecting a second maximum change in the output of the source driver 20 in which charge sharing is not applied to the current line data, and selecting the second maximum change as a second option level.

Thereafter, one of the first option level and the second option level is selected as the first option information to be applied to a packet, depending on whether to apply charge sharing to the previous line data.

The adaptive charge sharing control operation is specifically described with reference to FIG. 5.

First, if a display pattern is a dynamic pattern, in order to determine whether to apply charge sharing, the timing controller 10 stores previous line data (N-1 line) and current line data (N line) in the pixel value storage 5 (S30), and maps the previous line data (N-1 line) and the current line data (N line) (S32).

The display panel 30 is configured with pixels arranged depending on the packet type thereof. Illustratively, FIG. 6 is a diagram illustrating the arrangement of pixels of the normal type display panel 30. FIG. 7 is a diagram illustrating the arrangement of pixels of the Z-inversion type display panel 30. In FIGS. 6 and 7, an Rx-series pixel means a red pixel, a Bx-series pixel means a blue pixel, a Gx-series pixel means a green pixel, and a Du pixel means a dummy pixel.

The timing controller 10 configures a packet PKT by sorting display data depending on the type of the display panel 30 so that the red pixels, the blue pixels, and the green pixels are differently arranged in a line unit.

Therefore, the timing controller 10 invokes information for confirming the specifications of the display panel 30 in order to compare the previous line data (N-1 line) and the current line data (N line), and controls the pixel value storage 5 to perform the mapping for re-sorting the previous

line data (N-1 line) and the current line data (N Line) based on the specifications of the display panel 30.

Thereafter, the pixel value correction unit 6 corrects the previous line data (N-1 line) and the current line data (N line) to each have a polarity mapped for each channel based on packet data, based on information on a polarity of line data for each channel, provided by the packet mapper 4 (S34).

Thereafter, the timing controller 10 controls the operation unit 7 to calculate a power gain quantity (Ps) and power loss quantity (Pw) attributable to charge sharing for the current line data by comparing the previous line data and the current line data (S36). The power gain quantity (Ps) and the power loss quantity (Pw) may be calculated using a calculation equation preset in the timing controller 10.

The operation unit 7 may receive, from the packet mapper 4, information on a polarity of line data for each channel for the operations, and may perform the operations based on a positive polarity and a negative polarity.

As illustrated in FIG. 8, the source driver 20 according to an embodiment of the present disclosure may be configured to perform charge sharing on all channels based on an all-charge sharing connection. The source driver 20 includes a plurality of channels BF for outputting a source signal (Sout). All-charge sharing means that all the channels BF are connected in common to perform charge sharing.

In FIG. 8, the switching of the channels BF for the charge sharing may be implemented using a plurality of MOS transistors. Since the plurality of MOS transistors may be variously configured depending on a manufacturer's intention, a detailed example thereof is omitted.

In the all-charge sharing connection structure, a charge sharing voltage may be determined to have a level to which an average of the voltages of connected channels is applied.

Each of the channels BF may be configured to output a voltage having a positive polarity in a voltage range of an intermediate driving voltage (HVDD) or more or to output a voltage having a negative polarity in a voltage range of less than the intermediate driving voltage (HVDD). Furthermore, each of the channels BF performs charge sharing while being driven in a line unit. That is, each of the channels repeats the driving and the charge sharing based on pixel data varying in a line unit.

The channel BF that outputs the voltage having the positive polarity may drive an output in the range of the intermediate driving voltage (HVDD) to a driving voltage (VDD). The channel BF that outputs the voltage having the negative polarity may drive an output in the range of a ground voltage (VSS) to the intermediate driving voltage (HVDD). In this case, the intermediate driving voltage (HVDD) may be set as a voltage having a level between (e.g., middle) the driving voltage (VDD) and the ground voltage (VSS).

A charge sharing voltage having the positive polarity and the negative polarity, applied to all the channels BF, varies in a line unit, and is determined to have a level to which an average of the voltages of all the channels BF subjected to an all-charge sharing connection is applied. Therefore, a level of a charge sharing voltage may correspond to the positive polarity having the intermediate driving voltage (HVDD) or more or the negative polarity of less than the intermediate driving voltage (HVDD).

In a process of repeating the driving and the charge sharing, power saving and power consumption may be performed depending on a change in voltages of the channels BF.

If voltages of the channels BF are charged by a current discharged when the voltages vary from a driving voltage of a previous line to a charge sharing level or vary from the charge sharing level to a driving voltage of a next line, it may be understood that power saving is performed on the channels BF. In this case, the power saving may be used to calculate a power gain quantity (Ps) attributable to the charge sharing.

Furthermore, if power consumption occurs when voltages of the channels BF vary from a driving voltage of a previous line to a charge sharing voltage or vary from the charge sharing voltage to a driving voltage of a next line, the power consumption may be used to calculate a power loss quantity (Pw) attributable to the charge sharing.

As described above, the timing controller 10 controls the operation unit 7 to calculate the power gain quantity (Ps) and power loss quantity (Pw) attributable to the charge sharing for the current line data by comparing the previous line data and current line data for all the channels BF subjected to the all-charge sharing connection (S36).

When the power gain quantity (Ps) and the power loss quantity (Pw) are calculated, the option information providing unit 9 of the timing controller 10 compares the power gain quantity (Ps) and the power loss quantity (Pw) calculated by the operation unit 7, and checks whether the power gain quantity (Ps) is greater than the power loss quantity (Pw) (S38).

Illustratively, step S38 of checking whether the power gain quantity (Ps) is greater than the power loss quantity (Pw) may be configured to determine whether the power gain quantity (Ps) is greater than the power loss quantity (Pw) by a preset offset level or more.

When the power gain quantity (Ps) is equal to or smaller than the power loss quantity (Pw), the option information providing unit 9 of the timing controller 10 determines not to apply charge sharing to the current line data, determines charge sharing-off (S42), defines corresponding second option information, and provides the defined second option information to the packet configuration unit 12. Accordingly, the packet configuration unit 12 configures a packet PKT to which the second option information, indicating that charge sharing is not to be applied to the current line data, is applied (S44).

In contrast, when the power gain quantity (Ps) is greater than the power loss quantity (Pw), the option information providing unit 9 of the timing controller 10 determines to apply charge sharing to the current line data, determines charge sharing-on (S40), defines corresponding second option information, and provides the second option information to the packet configuration unit 12. Accordingly, the packet configuration unit 12 configures a packet PKT to which the second option information, indicating that charge sharing is to be applied to the current line data, is applied (S44).

As described above, if a display pattern is a dynamic pattern, the timing controller 10 may generate the second option information, indicating whether to apply charge sharing to a source signal corresponding to current line data, through the adaptive charge sharing control process such as FIG. 5, and may provide the source driver 20 with a packet PKT to which the second option information is applied.

The source driver 20 performs adaptive charge sharing on a source signal in order to reduce power consumption based on the second option information indicating that charge sharing is to be performed, and outputs a source signal normally without performing adaptive charge sharing based

on the second option information indicating that charge sharing is not to be performed.

The low power mode control operation is specifically described with reference to FIG. 9.

If a display pattern is a static pattern, the timing controller 10 may perform the low power mode control operation for reducing power consumption by controlling the amount of current for the output of the source driver 20, as in FIG. 9.

If a display pattern is a static pattern, the timing controller 10 stores previous line data (N-1 line) and current line data (N line) in the pixel value storage 5 (S70), and maps the previous line data (N-1 line) and the current line data (N line) (S72).

The timing controller 10 configures a packet PKT by sorting display data so that red pixels, blue pixels, and green pixels are differently arranged in a line unit depending on the type of the display panel 30.

Therefore, the timing controller 10 invokes information for confirming the specifications of the display panel 30 in order to compare the previous line data (N-1 line) and the current line data (N line), and controls the pixel value storage 5 to perform the mapping for re-sorting the previous line data (N-1 line) and the current line data (N Line) based on the specifications of the display panel 30.

Thereafter, the pixel value correction unit 6 corrects the previous line data (N-1 line) and the current line data (N line) to each have a polarity mapped for each channel based on packet data, based on information on a polarity of line data for each channel, provided by the packet mapper 4 (S73).

If a display pattern is a static pattern, the timing controller 10 checks a change in the output of the source driver 20 for the current line data and performs the low power mode control process of determining the first option information suitable for a maximum change.

Referring to FIG. 10, the first option information is indicated as PWRC and may be changed like "HHH", "LHH", or "LLL."

The first option information may be determined to control the amount of current in a range in which the output of the source driver 20 can be maintained based on line data having a static pattern.

As in FIG. 11, the first option information PWRC may be determined to be included in a range that satisfies time necessary to drive a screen and a minimum level (Min Level), and may be set in a line data unit in order to reduce the amount of current. That is, the first option information may be determined based on current line data in order to reduce the amount of current in a range in which an output voltage is maintained based on previous line data.

To this end, the timing controller 10 controls the operation unit 7 to compare the previous line data and the current line data.

The operation unit 7 of the timing controller 10 detects, as an absolute value, a first maximum change (Lpeak_cs) in the output of the source driver 20 in which charge sharing is applied to the current line data, by comparing the previous line data and the current line data, and detects, as an absolute value, a second maximum change (Lpeak_ncs) in the output of the source driver 20 to which charge sharing is not applied to the current line data, by comparing the previous line data and the current line data (S74).

The operation unit 7 of the timing controller 10 selects the first maximum change (Lpeak_cs) and the second maximum change (Lpeak_ncs), detected as described above, as a first option level and a second option level, respectively, and

11

determines control options (PWRCcs and PWRCncts) corresponding to the first option level and the second option level, respectively (S76).

Thereafter, the option information providing unit 9 of the timing controller 10 checks whether the charge sharing has been applied to the previous line data (S78).

If the charge sharing has been applied to the previous line data, the option information providing unit 9 of the timing controller 10 selects the control options (PWRCcs) as the first option information (PWRC) (S80), and provides the first option information (PWRC) to the packet configuration unit 12. A packet PKT may be configured by applying the first option information (PWRC) thereto (S84).

In contrast, if the charge sharing has not been applied to the previous line data, the option information providing unit 9 of the timing controller 10 selects the control options (PWRCncts) as the first option information (PWRC) (S82), and provides the first option information (PWRC) to the packet configuration unit 12. A packet PKT may be configured by applying the first option information (PWRC) thereto (S84).

If a display pattern is a static pattern, the timing controller 10 performs control for reducing power consumption by controlling the amount of current for the output of the source driver 20 through the low power mode control operation.

The timing controller 10 can reduce power consumption of the source driver 20 by performing the adaptive charge sharing control operation of FIG. 4 and the low power mode control operation of FIG. 9 every line data unit.

The timing controller 10 may perform the low power mode control process by considering each of the output buffer, the gamma buffer, and the intermediate driving voltage buffer, may generate separate option information for controlling the output buffer, the gamma buffer, and the intermediate driving voltage buffer, and may apply the separate option information to a packet PKT.

Accordingly, the source driver 20 may be controlled to reduce total current consumption because the output buffer, the gamma buffer, and the intermediate driving voltage buffer are controlled based on respective option information.

Through the aforementioned configurations and operations of the embodiments, the present disclosure can support the source driver that uses various charge sharing methods, such as the all-charge sharing connection, and provide an option for freely reducing power consumption with respect to a polarity, by correcting a polarity of line data based on a packet type and packet data.

Through the aforementioned configurations and operations, the present disclosure can reduce consumption power of the source driver 20 by recognizing, by the timing controller 10, a display pattern and transmitting, to the source driver 20, option information corresponding to the recognized display pattern.

Furthermore, the present disclosure can reduce consumption power by performing charge sharing control over the output of the source driver 20 or current control over at least one of the output buffer, the gamma buffer, and the intermediate driving voltage (HVDD) buffer, based on option information corresponding to a display pattern.

The present disclosure has effects in that it can support the source driver that uses various charge sharing methods, such as the all-charge sharing connection, and provide an option for freely reducing power consumption with respect to a polarity, by correcting a polarity of line data based on a packet type and packet data.

The present disclosure has an effect in that it can reduce consumption power of the source driver by recognizing, by

12

the timing controller, a display pattern and transmitting, to the source driver, option information corresponding to the recognized display pattern.

Furthermore, the present disclosure has an effect in that it can reduce consumption power by performing charge sharing control over the output of the source driver or current control over at least one of the output buffer, the gamma buffer, and the intermediate driving voltage (HVDD) buffer, based on option information corresponding to a display pattern.

While various embodiments have been described above, it will be understood to those skilled in the art that the embodiments described are by way of example only. Accordingly, the disclosure described herein should not be limited based on the described embodiments.

What is claimed is:

1. A low power driving system for a display device, comprising:

a timing controller configured to receive packet data for correcting a polarity of line data correct polarities of previous line data and current line data based on the packet data, divide a display pattern into a static pattern and a dynamic pattern based on a difference between the previous line data and the current line data, and transmit a packet to which one of first option information corresponding to the static pattern and second option information corresponding to the dynamic pattern is applied; and

a source driver configured to receive the packet and perform a low power mode corresponding to the static pattern based on the first option information or adaptive charge sharing corresponding to the dynamic pattern based on the second option information,

wherein the timing controller is further configured to: calculate a power gain quantity and power loss quantity attributable to charge sharing for the current line data based on a result of a comparison between the previous line data and the current line data, and

provide the second option information on whether to apply charge sharing to the current line data based on a result of a comparison between the power gain quantity and the power loss quantity.

2. The low power driving system of claim 1, wherein the timing controller

provides the second option information for charge sharing-off for the current line data when the power gain quantity is equal to or smaller than the power loss quantity, and

provides the second option information for charge sharing-on for the current line data when the power gain quantity is greater than the power loss quantity.

3. The low power driving system of claim 1, wherein the timing controller calculates the power gain quantity and power loss quantity attributable to the charge sharing for the current line data by comparing the previous line data and current line data with respect to all channels of the source driver subjected to an all-charge sharing connection.

4. The low power driving system of claim 1, wherein the source driver performs the adaptive charge sharing for selectively performing charge sharing on a source signal, corresponding to the current line data, based on the second option information.

5. The low power driving system of claim 1, wherein the timing controller

computes a first maximum change in an output of the source driver in which charge sharing is applied to the current line data and a second maximum change in the

output of the source driver in which charge sharing is not applied to the current line data based on a result of a comparison between the previous line data and the current line data, and

provides, as the first option information, one change 5 selected depending on whether to apply the charge sharing to the previous line data, among the first maximum change and the second maximum change.

6. The low power driving system of claim 5, wherein the timing controller 10

provides the first maximum change as the first option information if the charge sharing is applied to the previous line data, and

provides the second maximum change as the second option information if the charge sharing is not applied 15 to the previous line data.

7. The low power driving system of claim 5, wherein the source driver performs the low power mode in which an amount of current to maintain an output of the current line data is reduced based on one of the first maximum change 20 and the second maximum change provided as the first option information.

8. The low power driving system of claim 1, wherein: the timing controller provides the first option information comprising information for distinguishing among an 25 output buffer, a gamma buffer, and an intermediate driving voltage buffer, and

the source driver performs the low power mode on one buffer selected based on the first option information, among the output buffer, the gamma buffer, and the 30 intermediate driving voltage buffer.
